EDWARD JAMES WARING, OF PLAINFIELD, NEW JERSEY, ASSIGNOR TO PYRENE MANUFACTURING COMPANY, OF NEWARK, NEW JERSEY, A CORPORATION OF NEW JERSEY.

DOOR LATCH.

Application filed September 28, 1925. Serial No. 58,963.

This invention relates to door latches and is herein illustrated as applied to the latches used in connection with fire doors, especially such doors as are frequently or always swung 5 to by a spring or weight. Such doors frequently have three separate latches, near the top, bottom, and middle, respectively, for latching the door in its closed position and these latches are usually linked together so 10 that a single handle will open them all at the same time and so that a single spring may be used to assist in drawing them down to effective or latching position. Such doors are usually of heavy construction and consider- 15 able weight and in consequence thereof it has frequently happened that one or more of the latches have become inoperative under the severe blows of closing the door, which is usually slammed to shut position. In a 20 large factory the expense of maintaining such latches on fire doors in good working condition has amounted to a serious item of cost.

According to the present invention these 25 difficulties are avoided by providing an automatic operating device which does all the work of lifting the latches as the door swings to, thus preventing the latches from impinging upon the catches as the door approaches closed position. When, however, 30 the door reaches closed position the latches fall and hold the door closed in the usual manner. The cam-follower may be upon an arm longer than the usual latch arms, and 35 may be operated by a fixed member having an operating face at a reduced angle, thus reducing the severity of the blow when the door slams shut. Moreover the contact faces 40 of the operating device may be especially hardened to endure the hard service to which they are usually subjected.

Other features and advantages will hereinafter appear.

In the accompanying drawings Figure 1 45 is a front view of part of a fire door and part of the adjacent wall showing the latches in effective position holding the door closed.

Figure 2 is a sectional side view showing the parts in the same position.

Figure 3 is a perspective detail of the cam follower and its operating cam, showing the position of the parts when the door is shut.

In one ordinary form of fireproof construction a fire door 1 swinging on hinges 50 (not shown) is drawn by a weight or spring

(not shown) to the closed position shown in Figure 1, in which latches 2, 3 and 4 projecting beyond the edge, hold the door closed by falling behind flat-topped catch lugs 5 projecting from catch bodies 6, supported from or set into the wall 7 near the door jamb. In this position the latches 2, 3, 4 lie substantially against the face of the wall 7. Each of these latches 2, 3, 4 turns on its pivot 8, which is supported in its respective plate 9, suitably fastened to the door 1. For holding the latches close to the face of the door there is provided for the top and bottom latches 2 and 4 an overlying guide plate 10, which provides an elongated guide 60 opening in which the latches swing up and down freely but are limited in their movement by the offset ends 11, which lie against the face of the door and are secured thereto by bolts or other holding devices 12. In 65 order to release the latches to open the door there is provided a handle 13 which is fast to a cam 14 turning on a suitable pivot in the door so that by rocking the handle 13 the lifting portion 15 of the cam rises and 70 lifts a latch (usually and as shown the middle latch 3) against the force of the spring 16, which normally holds the latch downward at its locking position. In order to 75 operate the latches 2, 3 and 4 together at the turning of the handle 13 they are connected by a link 17 which is provided with suitable pivots 18, one for each of the latches 2, 3 and 4. For convenience the link 17 is 80 perforated with a number of openings 19 through which the pivots 18 may be adjusted 85 to fit the height of the various catch bodies 6. 90

According to the present invention there is provided an operating device for operating all of the latches 2, 3 and 4. In the 95 form of the invention illustrated herein the top latch 4 is provided with an extension 20 which forms part of the operating device. Owing to the fact that the extension 20 is near the top of the door, it is out of the 100 way and will not interfere with the passage of people or goods through the doorway, even though the door is only partially opened. The device also includes a roller-follower 21, which is suitably pivoted upon lugs 22 on the extension 20, and a stationary lifting lug 24 secured to the wall and having an inclined lifting face 23. As the door 105 swings toward closed position the roller-follower 21 strikes the inclined face 23 of 110

the lifting lug 24 and rides up this inclined face, lifting the latches 2, 3 and 4 clear of the respective inclined operating faces 25 of their catches, but permitting them to freely drop behind their catches by dropping clear of its inclined lifting face. In the form of the invention herein illustrated each catch 6 has the usual flat summit 27. On this the latch may rest and slide easily just before it falls into its holding notch 26.

Since the flat summits provide slides which support the latches, it becomes unnecessary to provide a fine adjustment between the follower 21 and its operating face 23. All that the follower has to do is to lift the latches 2, 3, and 4 on to the respective summit slides 27 and then let the momentum of the door push the latches easily over the slides so that they will drop into their notches 26. For this reason the structure is shown as including a notch 28 in the lifting lug 24 which is wider than the notches 26 to admit the roller-follower 21. Since the top catch 5 holds the top latch 4, there is no need for the roller-follower to fit the notch 28 closely.

The lifting lug 24 projects from a plate 29 which is held flat against the wall by suitable fastening means, such as screws 30. There may be a reinforcing piece of hardened metal forming the lifting face 23, secured to the lifting lug 24, as by screws 32, to provide a broad bearing on which the roller-follower 21 will run without wearing it down. The lifting lug 24 need not be hardened but may be of any material suitable for attaching to the wall in the usual manner. The roller-follower 21 may be provided with a stub-shaft 33 at each end, these shafts turning in looped hangers 34 held by screws or bolts to the extension 20, so that the roller-follower turns on the loops in a notch 35 in the extension 21 with the stub shafts thrusting upwardly against shallow bearings 36 cut in the extension 21, thus permitting the lug 23 to be approximately aligned with the corresponding catch 6. It will be noted, however, that the slope of the cam face 23 is materially less steep than the slope of the corresponding faces 25. This is advantageous as minimizing the load on the follower 21, and the longer projection of the lug 24 is unobjectionable at the height of the top latch 4, although a projection of the same length might be very objectionable lower down on the door.

It will be noted that the mechanism is simple and can be made as heavy as desired,

thus enabling the device to be used in connection with heavy fire doors which are released by a fusible link and slammed shut by powerful mechanism or heavy weights.

Having thus described certain embodiments of the invention, what is claimed is:—

1. In combination, a door, a latch, a catch adapted to receive said latch in retaining position, a latch-lifting member connected to said latch, and a latch-operating device spaced from said catch and adapted to be engaged by said latch-lifting member as the door is being closed and thereby move said latch with respect to said catch into position to be received by said catch.

2. In combination, a door, a latch projecting beyond the edge of the door, a catch adapted to receive said latch in retaining position, a latch-operating arm projecting beyond the edge of the door, means connecting said latch with said latch-operating arm, and an operating lug adapted to be engaged by said arm as said door is being closed and move said arm whereby said latch is moved with respect to said catch into position to be received by said catch.

3. In combination, a door, a latch pivoted to said door, a catch having a notch adapted to receive said catch, a latch-lifting member connected to said latch, and a latch-operating member, said operating member being provided with an inclined face adapted to be engaged by said latch-lifting member and lift the same with respect to said catch as the door moves shut and having a notch into which said latch-lifting member is adapted to move from said inclined face as the door reaches closed position whereby said latch is permitted to drop into the notch of said catch.

4. In combination, a door, a plurality of latches pivoted to said door, a catch for each of said latches, each catch being provided with a notch adapted to receive its respective catch, a latch-lifting arm, means pivotally connecting said arm to said latches, and a latch-operating member, said operating member being provided with an inclined face adapted to be engaged by said arm and lift the same as the door moves shut and having a notch into which said arm is adapted to move from said inclined face as the door reaches closed position whereby said latches are permitted to drop into the notches of their respective catches.

In testimony whereof, I have affixed my signature to this specification.

EDWARD JAMES WARING.
